[21] Appl. No.: 167,306

[57] CLAIM

The ornamental design for a data terminal printer, as
shown and described.

DESCRIPTION

FIG. 1 is a left front perspective view of a data terminal
printer showing our new design;

FIG. 2 is a left rear perspective view of the data terminal
printer;

FIG. 3 is a side elevational view of a data terminal
printer.

The broken lines are shown for illustrative purposes
only.
